P. W. SMITH, OF CHICOPEE FALLS, MASSACHUSETTS.

Letters Patent No. 83,332, dated October 20, 1868.

IMPROVEMENT IN DEVICE FOR FASTENING SHIRT-COLLARS.

The Schedule referred to in these Letters Patent and making part of the same.

To all whom it may concern:

Be it known that I, P. W. SMITH, of Chicopee Falls, Hampden county, Commonwealth of Massachusetts, have invented a new and useful Paper-Collar Button; and I do hereby declare that the following is a full and exact description thereof, reference being had to the accompanying drawings, and to the letters of reference marked thereon.

In the drawings—

Figure I is a side view;

Figure II is an end view; and

Figure III shows my invention in place in the collar.

This invention consists of a button, so formed that a paper collar may be fastened by it securely and conveniently, without requiring the button-holes to be stretched while doing so, thereby removing the risk of tearing them, and the collar can be taken off with equal ease. It is also constructed so that it remains in one position in the button-hole, serving to conceal them from view when no cravat or tie is worn, and also affording a fastening-place for a knot or bow with elastic, when such is desired to be worn.

In construction, I form my paper-collar button with a round centre-plate, A, with two necks, *a* and *b*, the one, *a*, projecting towards the front, and having an oblong flange, B, formed on its end, and the other, *b*, extending in an opposite direction from the other side of the plate A, with a circular flange, C, formed upon it.

The neck *b*, with its flange C, serves to connect the end of the collar-band of the shirt, thus fastening the shirt at the throat, while the ends of the paper collar are fastened on the front side of the plate A by means of a neck, *a*, and its oblong flange.

It will be seen in the drawings that this flange B is made about the size and shape of the button-hole of the collar, so that the latter can be placed over it with-

out stretching or tearing when the button is in position shown in Fig. III.

Upon the plate A is placed a pin, D, projecting to the front, and extending about half the distance between the plate A and one end of the flange B at this point.

The method of fastening the collar upon this button (it being placed in the neck of the shirt) is as follows:

The end of the collar nearest the pin D is first put over the neck *a*, and rests against the flat surface of the plate A, the pin D extending through the button-hole, and preventing the button from turning. The other end of the collar is then fastened by being hooked over the flange B, catching against the neck *a*. This is shown in the figure, where it is also seen that scarcely any of the button-hole of the outer end of the collar is exposed to view, and none of that of the inner one, so that a person, without examining carefully, could find no clue to the material of the collar, which, in ordinary cases, becomes perfectly obvious, from the appearance of the button-hole, when no cravat is used. Besides this, the ends of the collar, resting against the flat surface of the plate A, do not get crumpled by the movements of the neck.

Now, having described my invention,

What I claim as new, and desire to secure by Letters Patent, is—

The combination of the plate A, necks *a* and *b*, with oblong and circular flanges, B and C, and pin D, the parts being constructed and arranged substantially in the manner and for the purpose set forth.

P. W. SMITH.
